RESEARCH TEST MISSILE

Ernst A. Steinhoff, Donald L. Baker, Hans U. Schuerch, and Charles R. Herrmann, all of Santa Barbara, Calif., assignors, by mesne assignments, to Curtiss-Wright Corporation, a corporation of Delaware

Application April 3, 1958, Serial No. 50,328

Term of patent 14 years

(Cl. D71—1)

FIG. 2

FIG. 3

FIG. 1

Figure 1 is a perspective view of a research test missile, showing our new design;

Figure 2 is a front view thereof; and

Figure 3 is a rear view thereof.

We claim:

The ornamental design for a research test missile, substantially as shown.
